UNITED STATES PATENT OFFICE.

WALTER H. PRUEFER, OF PROVIDENCE, RHODE ISLAND, ASSIGNOR TO FISCHER AND PRUEFER, OF PROVIDENCE, RHODE ISLAND, A FIRM COMPRISING SIGMUND FISCHER AND WALTER H. PRUEFER.

BRACELET.

1,304,706.

Specification of Letters Patent. Patented May 27, 1919.

Application filed January 3, 1916, Serial No. 69,761. Renewed April 8, 1919. Serial No. 288,654.

To all whom it may concern:

Be it known that I, WALTER H. PRUEFER, a citizen of the United States, and resident of the city of Providence, in the county of Providence and State of Rhode Island, have invented certain new and useful Improvements in Bracelets, of which the following is a specification.

This invention relates to flexible bracelets of the non-extendible type and has for its object to construct such a bracelet of a series of units each comprising a box shaped member the same being connected into a flexible chain adapted to be used as a bracelet.

15 let or other similar article of jewelry.

A further object of the invention is to provide an H-shaped link for connecting these box shape members yieldably together.

The invention further consists in the provision of a closing plate for the back of the box and in rolling the edges of the box inwardly and over onto the plate to permanently lock and hold the whole in position.

With these and other objects in view, the invention consists of certain novel features of construction, as will be more fully described and particularly pointed out in the appended claim.

In the accompanying drawings:

30 Figure 1— is a side view of my improved bracelet.

Fig. 2— is an edge view showing the series of the box members connected together.

Fig. 3— is a face view showing a blank as 35 cut from sheet stock into a shape from which the box is struck.

Fig. 4— is a perspective view of the box after having been drawn up into a hollow form.

40 Fig. 5— is a perspective view of the H-shape link which joins the box members together.

Fig. 6— is a perspective view showing the ends of the box as slotted from its margin 45 inward and an H-shaped link in position in one of these slots.

Fig. 7— is a perspective view showing the back plate which fits into and is secured in the box link.

50 Fig. 8— is a sectional elevation showing a number of the box members as connected together by H-shaped links also showing the back plate as being secured in the box by

rolling the edge of the latter over onto that of the former.

Fig. 9— is an enlarged view of the snap catch which releasably secures the opposite ends of the bracelet together.

Fig. 10— is a sectional elevation showing the snap as connecting the two adjacent 60 links together.

Fig. 11— is a perspective view illustrating the construction of the end of the box showing the lip portion which is releasably engaged by the shoulders of the catch member 65 connected to the opposite end of the bracelet.

Referring to the drawings 10 designates the blank as cut from sheet stock from which the box member is drawn up. This 70 blank may be made of any suitable material, but bracelets and chains of this construction are usually made of a heavy rolled plated stock. After the blank has been cut from the sheet metal, it is then struck and drawn 75 up into boxform as illustrated in Fig. 4 the corners being notched as at 30 to permit of the edges of this box being subsequently rolled over inwardly.

After the box has been drawn up into 80 the desired form the end walls 12 are slotted as at 13 inwardly from their margin 14.

The connecting link member 15 is preferably formed in the shape of the letter H, the cross bar portion 16 being of a width 85 to be passed into and fit loosely in the slot 13 and the legs 17 and 18 are designed to pass into adjacent boxes and abut against their inner end walls thus loosely connecting these box members together.

90 In order to close the back of this box, I have provided a plate 19 which is of a shape to fit into the box along the dotted line 20, see Fig. 6, and after being positioned therein the edges 14 and 31 of the 95 box are rolled over inwardly onto the plate thereby providing a secure fastening for holding both the back and the H-link firmly in their respective boxes.

By this construction, it will be seen that 100 the base metal about the edge of the back is turned inward by the rolling of the edge, so that only the outer surface of precious metal is exposed.

105 In order to connect the adjacent ends of this chain or bracelet together, I have pro-

vided a catch member 21, see Fig. 9, having its body portion formed of spring metal and folded over and back upon itself, one end of the body portion is provided with recesses 22 cut inward from its opposite edges, thereby forming a head or leg 23 to engage the inner wall of one of the end links and also providing a bar portion 24 which enters the slot 13 in the end wall of the box by which construction this catch is connected to the said box link. The opposite end 25 of the body portion is provided with a presser extension 26 turned outwardly and the shoulders on each side of this extension are adapted to engage the end walls 27 of the end link 28 so that when it is desired to release this catch it is only necessary to force this presser member 26 inward and the shoulders 29 are disengaged from the edge 27 of the link 28 permitting this catch to be readily withdrawn and the chain or bracelet separated.

By my improved construction of chain or bracelet the box members may be made of inexpensive plated material and when completed none of the base metal is exposed and these box shaped links are readily connected or assembled into a series of links

connected together by means of a simple form of H-shaped link which permits the necessary and desirable amount of flexibility to the chain.

I have shown and described one way of constructing the links of my improved box chain or bracelet but the detail of this construction may be varied without departing from the spirit and scope of my invention.

I claim:

A bracelet constructed of a series of units, each unit comprising a body formed of a single piece of sheet metal having portions bent at an angle to provide side and end walls, said end walls being slotted from their marginal edges, a cover plate, the marginal edges of said side and end walls being bent over said plate, and links connecting contiguous units, each link being headed and provided with a shank passed through the slots of contiguous end walls of adjacent units.

In testimony whereof I affix my signature in presence of two witnesses.

WALTER H. PRUEFER.
